J. J. SULLIVAN,
RESERVE SUPPLY VALVE FOR LIQUID FUEL TANKS,
APPLICATION FILED NOV. 26, 1919.

1,413,069.

Patented Apr. 18, 1922.

John J. Sullivan, INVENTOR.

BY *Albert M. Moore,*
His ATTORNEY.

UNITED STATES PATENT OFFICE.

JOHN J. SULLIVAN, OF LOWELL, MASSACHUSETTS.

RESERVE-SUPPLY VALVE FOR LIQUID-FUEL TANKS.

1,413,069.

Specification of Letters Patent. Patented Aug. 16, 1922.

Application filed November 29, 1919. Serial No. 899,358.

To all whom it may concern:

Be it known that I, JOHN J. SULLIVAN, a citizen of the United States, residing at Lowell, in the county of Middlesex and Commonwealth of Massachusetts, have invented a certain new and useful Improvement in Reserve-Supply Valves for Liquid-Fuel Tanks, of which the following is a specification.

10 This invention relates to reserve supply valves for liquid fuel-tanks, and is adapted for use with the fuel-tanks of automobiles, air-ships and power launches.

The object of this invention is to provide 15 means for keeping a reserve supply in the fuel-tank until needed; to make it evident when the main supply is exhausted; to draw the liquid fuel, both the main supply and the reserve supply wholly through the top 20 of the tank; and thus to prevent any leakage from the bottom of the tank; to make it possible to remove the supply line or the reserve supply valve from the tank with the least soiling of the tank and connected parts.

25 This invention comprises two tubes, an outer tube secured in the top of the tank and extending nearly to the bottom of the same, but without passing through the bottom or connecting with any opening in said

30 bottom, and an inner tube which has a turning fit in said tube. These tubes are both open at the bottom at all times and the inner tube turns in the outer tube without advancing.

The outer tube is connected to the supply 35 line which runs to the carburetor. The inner tube is also provided with a lateral opening which registers with a corresponding opening in the outer tube at the top of the desired reserve.

40 The upper end of the inner tube is provided with a suitable handle by which it may be turned to bring the lateral openings of the two tubes into register with each other, so that when the liquid fuel in the tank is drawn below the tops of these lateral openings the liquid fuel can not be drawn through the tubes into the supply-line, the failure of the fuel causing the engine to stop and serving as an alarm or signal.

45 In the accompanying drawing, Fig. 1, is 50 a side elevation of a liquid-fuel tank, partly in section with the reserve valve in central vertical section, connected to the pipe line of an internal combustion engine, said valve 55 being in a position to admit air to the sup-

ply line. Fig. 2 is like Fig. 1, except that the valve is in position to exhaust the reserve.

The tank A, elbow C secured in the bushing B, and the pipe line D leading from the tank to the carburetor (not shown) through said elbow, are of any usual construction, except as hereininafter stated, the bottom *a'* of the tank being unperforated, the ends of said elbow being externally threaded, one end *a* thereof being screwed into said bushing B and the other end *a'* connected by a compression-nut E to the pipe line or supply-pipe D.

The bore of the vertical end or arm *c* of the elbow is continued up through the top of the elbow and the outer tube F or case of the valve is arranged in and fits said vertical bore and preferably extends above said elbow in an air and watertight manner and is prevented from turning in said elbow, as, by soldering.

The valve proper F' or movable part of the valve is arranged in and fits the outer tube in an air and gas-tight manner but not so closely that the inner tube may not be readily turned in the outer by means of a suitable handle G.

The movement of the tube F' about its axis is limited, in any convenient manner, as by a radial stud *g* rigidly secured to said inner tube and projecting through a slot *g'* in the outer tube above the elbow. Said stud *g* is preferably screw-threaded and passes through the handle G, thus serving the further purpose of securing said handle to the tube F', the hub *g''* of said handle reaching below the slot *g'* near the top of the inner tube F'. After removing the screw-stud *g* the inner tube may be drawn out of the outer tube to be cleaned from dirt or sediment. The lower ends of the tubes F F' of the valve are open at all times.

The upper end portion of the outer tube F has a lateral opening *f* in alignment with the supply line and the inner tube has a lateral opening *f'* on each side arranged to register with said opening *f* when the stud *g* is at either end of the slot *g'* leaving a continuous passage from the interior of the tank to the supply-line.

Both of the tubes F F' may and one of them must reach down in the tank nearly to the bottom *a'* of said tank in order to exhaust the reserve-supply. Each tube F F' is

is provided at the level of the desired reserve supply with an opening $\frac{f^2}{f^3}$ which by turning the inner tube may be made to register with the corresponding reserve opening 5 in the other tube so that when the fuel supply has fallen to the level of these openings the engine will cease to operate because of drawing air instead of fuel to the carburetor. Obviously either of the tubes F F' may be 10 cut off just below the reserve openings $\frac{f^2}{f^3}$ without preventing the operation of the device. The upper end of the inner tube may be 15 closed by a plug $\frac{f^4}{f^5}$ to avoid the necessity of special care in fitting the handle G to said tube.

I claim:

The combination of a tank, two tubes arranged one within the other in the tank, one of the tubes being secured to the top of the 20 tank and the second being rotative relative thereto and extending above said top, both of said tubes having openings at the level of the reserve supply adapted to be brought into and out of register with each other by 25 appropriate turning of the second tube, releasable means normally holding the second tube against endwise movement and permitting said second tube to be withdrawn from the tank, and means to turn the second tube. 30

JOHN J. SULLIVAN.
